UNITED STATES PATENT OFFICE.

JAMES A. STEVENSON AND LEWIS O. PHILLIPS, OF NEW CASTLE, PENNSYLVANIA.

WATER-CLOSET.

No. 879,421.

Specification of Letters Patent.

Patented Feb. 18, 1908.

Application filed May 5, 1906. Serial No. 315,273.

To all whom it may concern:

Be it known that we, JAMES A. STEVENSON and LEWIS O. PHILLIPS, citizens of the United States of America, residing at New Castle, in the county of Lawrence and State of Pennsylvania, have invented certain new and useful Improvements in Water-Closets, of which the following is a specification, reference being had therein to the accompanying drawing.

Our invention relates to a new and useful improvement in water closets, urinals, slop hoppers and similar devices of a well known variety which depend upon siphonic action to carry away the contents of the bowl.

The fundamental idea involved in our invention is to provide a device, of the character described, which will obviate the necessity of a storage tank for supplying additional water to the bowl to cause siphonic action, and likewise provide a means whereby only a normal supply pipe need be used; as any ordinary low pressure house supply will be sufficient to cause our device to flush properly without the use of a storage tank or an enlarged supply pipe.

In the accompanying drawings in two sheets forming a part of this specification we have shown several different views of our device, Figure 1 being a longitudinal section on line 1—1 of Fig. 2. Fig. 2 is a plan view partly in section. Fig. 3 is a rear vertical section on line 3—3 of Fig. 2. Fig. 4 is a cross sectional view on line 4—4 of Fig. 3. Fig. 5 is a vertical section on line 5—5 of Fig. 2, and Fig. 6 is a sectional view of a portion of the rim on line 6—6 of Fig. 2.

Throughout the drawings the numeral 1 indicates the body portion of the closet which is constructed in the usual manner well known to devices of this character, and on the inside is the bowl 2.

Communicating with the lower portion of the bowl 2 is an inverted U shaped pipe 2' which forms an air trap 3, is part of the outlet system of our device, and is the essential feature which we employ to carry out our idea; the detailed part of which will be hereinafter more specifically described. The two legs of this pipe are designated by A and B. The lower end of the leg B communicates through an opening 3' with another inverted U shaped pipe 4, having legs C and D respectively, which constitutes the remaining por-

tion of the discharge system, and is located 55 alongside and in close proximity to the pipe 2'. The lower end of the leg D is connected at the floor line with the soil pipe, and at this point in said leg D there is arranged a widened out portion 4' ending in a shelf 4''. This construction is intended for the purpose of breaking the column of water passing down through leg D and insure better siphonic action.

In the rim portion 5 of the bowl there is 65 formed a storage chamber 6 which is of any desired capacity, while adjacent thereto and separated by a partition 7, is a flushing rim 8 from which a plurality of openings 9—9 communicate with the bowl 2.

Formed in the rear portion of the rim, and separated from the storage chamber 6 by a partition 10, is an air chamber 11, through the top of which passes an escapement duct 12, one end communicating with the storage 75 chamber 6, and the opposite end with the rear of the bowl. This duct acts as an air relief for said storage chamber until said chamber is filled with water; also affords a means for taking care of the overflow from said chamber and likewise admits air to prevent a vacuum in said chamber while it is emptying.

Arranged in the front part of the storage chamber 6 is a goose neck air trap 14, Fig. 1, communicating with a passage 15, which 85 empties into the bowl at any desired point, the free end entering a pocket or depression 16 formed in the bottom of the chamber 6. This goose neck trap is utilized for the purpose of holding the water in said storage 90 chamber until needed, as will be more fully described further on, while the free end of the goose neck is placed in the depression before mentioned for the purpose of insuring the complete emptying of said chamber.

Arranged through the rear wall of the bowl is a drain passage 17, Fig. 1, the upper end communicating with the air chamber 11 and the lower end with the leg A at any desired point.

Water is admitted from an ordinary house supply pipe 18, Fig. 3, having either high or low pressure, and is distributed simultaneously to three different parts of our device: the admission of water being regulated 10 by any suitable valve means or flushometer 19, or else controlled by hand.

One branch supplies the air chamber 11

through a pipe 20, while another pipe 21 supplies the flushing rim 8, and has a branch 22 leading to the storage chamber 6.

The said supply pipe 18 enters the connection 23 at a sharp angle, in order that the flow of water will be forced to air chamber 11 and not to air trap 3 and at the same time will trap end of pipe 24 and prevent any air from escaping from the air trap 3 through the connection 24 and 25 during the filling process.

Leading from the connection 23 to the air trap 3 is a pipe 24, and connecting with the pipe 20 is another pipe 25 which communicates with the interior of the siphon leg 4. Leading from the air chamber 11, which it enters on about the same level as the supply line 20, is a pipe 26 which in turn connects with the pipe 24 and conducts the air from air chamber 11 to air trap 3 when air chamber 11 is filling with water.

The operation of our invention is as follows:—Water stands in the bowl 2 to the height of the overflow point X; also in the siphon legs A, B and C at same level, these two independent bodies of water acting as a seal to the air trap 3 during filling process. When water is turned on, or admitted to a main supply pipe 18 controlled by any automatic valve means, or by hand, it will go to the storage chamber, flushing rim and air chamber, also to the bowl in the manner heretofore described. As the water enters the air chamber 11 it compresses the air contained therein and forces the same out through the pipe 26 and into the air trap 3; the vent 17 being much smaller than the supply opening, will allow of said chamber being nearly filled with water, and the air contained therein forced into the trap 3, before siphonic action takes place and after said action the said air chamber empties itself through said duct 17 by getting an air relief from leg D through pipes 25 and 20. The air being forced into the trap 3 from said chamber 11 through pipe 26 will be prevented from escaping to siphon leg D by reason of the flow of water sealing the ends of the pipes 24 and 25, while said water is flowing through pipe 20 and by the seal caused by the water standing in legs A and B. The air being forced into the trap 3 will back up the water in the bowl, and likewise in the siphon leg C, which, together with the water coming from the storage chamber, flushing rim and air chamber, will cause a sufficient head of water to be accumulated in bowl 2 above overflow point x to insure proper siphonage when air is released.

When the water in the bowl fills to a sufficient height to insure siphonage action, and overcome the air seal confined in the trap 3, the supply is shut off either by an automatic valve, flushometer, or else by hand. The instant said supply is shut off, the air con-

fined in trap 3 escapes rapidly through pipes 24, 20 and 25 into siphon leg D at 4, and, this obstruction being removed, the head of water stored in the bowl will escape through outlet pipes 2' and 4 with siphonic action.

As water rises in the bowl and immerses the lower end of the duct 15, air begins to compress in the goose neck of the siphon 14 and in so doing traps the water in the storage chamber until the water in the bowl recedes from the end of said duct 15, when the air in trap of goose neck will escape and be followed by all the water contained in said storage chamber; thus assisting in thorough washing out of the bowl and also leaves a sufficient after fill ready for the next operation. The drip from the air chamber through duct 17 into outlet pipe 2' will also assist in after filling of bowl.

Having thus shown and described our invention, what we claim, and desire to secure by Letters Patent is:

1. In a device of the character described, a suitable bowl; a chamber for the storage of water formed in the upper portion of said bowl, a flushing rim formed adjacent to the storage chamber, an air chamber, means for introducing water into the storage chamber flushing rim and air chamber, an air trap provided by an inverted U-shaped passage, one leg communicating with the bowl and the other leg with a second inverted U-shaped passage, means for introducing air from the air chamber into the trap during the filling process, and means for exhausting air from said trap during the emptying process.

2. In a device of the character described, a suitable bowl, a chamber, for the storage of water, formed in the upper portion of said bowl; means for introducing water into the chamber; means for trapping and holding the water in said chamber; and means for introducing water into the bowl from said chamber, when released.

3. In a device of the character described, a suitable bowl; a chamber, for the storage of water, formed in the rim of said bowl; means for introducing water into the chamber; an air trap in said chamber; and a duct leading from said air trap to any suitable point in the bowl.

4. In a device of the character described, a suitable bowl; a chamber, for the storage of water, formed in the upper portion of said bowl; a flushing rim having a plurality of ports therein communicating with the bowl; means for introducing water into the storage chamber and flushing rim; an air trap in said storage chamber; and a duct leading from said air trap to the bowl.

5. In a device of the character described, a suitable bowl; a chamber, for the storage of water, formed in the upper portion of said bowl; a flushing rim formed adjacent to the

storage chamber having a plurality of ports therein communicating with the bowl; an air chamber; means for introducing water simultaneously to the storage chamber, flushing rim and air chamber; an air trap in said storage chamber; and a duct leading from said air trap to the bowl.

6. In a device of the character described, a suitable bowl; a chamber, for the storage of water, formed in the upper portion of said bowl; a flushing rim formed adjacent to the storage chamber having a plurality of ports therein communicating with the bowl; an air chamber formed in the rim of said bowl; a venting duct formed through the air chamber, one end communicating with the storage chamber, and the other end with the bowl; means for introducing water simultaneously to the storage chamber, flushing rim and air chamber; an air trap in said storage chamber; and a duct leading from said air trap to the bowl.

7. In a device of the character described, a suitable bowl, a chamber for the storage of water formed in the upper portion of said bowl, a flushing rim formed adjacent to the storage chamber, an air chamber, means for introducing water into the storage chamber, flushing rim and air chamber, means for trapping and holding water in the storage chamber, means for introducing water into the bowl from said chamber when released, an air trap provided by an inverted U-shaped passage, one leg communicating with the bowl and the other leg with a second inverted U-shaped passage, means for introducing air from the air chamber into the trap during the filling process, and means for exhausting air from said trap during the emptying process.

8. In a device of the character described, a suitable bowl; a chamber, for the storage of water, formed in the upper portion of said bowl; an air trap provided by an inverted U shaped passage, one leg communicating with the bowl and the other with a second inverted U shaped passage somewhat higher than the former; means for introducing air into the trap during the filling process and means for exhausting the air from said trap during the emptying process.

9. In a device of the character described, a suitable bowl; a chamber, for the storage of water, formed in the upper portion of said bowl; a flushing rim formed adjacent to the storage chamber, having a plurality of ports therein communicating with the bowl; an air chamber formed in the rim of said bowl; means for introducing water simultaneously to the storage chamber, flushing rim and air chamber; an air trap in said storage chamber; a duct leading from said air trap to the bowl; an air trap provided by an inverted U shaped passage, one leg communicating with the bowl and the other leg with a sec-

ond inverted U shaped passage somewhat higher than the former; means for introducing air from the air chamber into the trap during the filling process and means for exhausting air from said trap during empty- 70

10. In a device of the character described, a suitable bowl; a chamber, for the storage of water, formed in the upper portion of said bowl; a flushing rim formed adjacent to the storage chamber, having a plurality of ports communicating with the bowl; an air chamber formed in the rim of said bowl; an air trap in said storage chamber; a duct leading from said air trap to the bowl; means for introducing water simultaneously to the storage chamber, flushing rim and air chamber; an overflow duct formed through the air chamber, one end communicating with the storage chamber and the other end with the bowl; an air trap provided by an inverted U shaped passage, one leg communicating with the bowl and the other leg with a second inverted U shaped passage somewhat higher than the former; a duct leading from the air chamber to a point in the discharge line; means for introducing air from the air chamber into the air trap during the filling process; and means for exhausting air from said trap during emptying process. 75 80 85

11. In a device of the character described, a suitable bowl; a chamber, for the storage of water, formed in the upper portion of said bowl; a flushing rim formed adjacent to the storage chamber, having a plurality of ports communicating with the bowl; an air chamber formed in the rim of said bowl; an overflow duct formed through the air chamber; an air trap in said storage chamber; a duct leading from said air trap to the bowl; an air trap provided by an inverted U shaped passage, one leg communicating with the bowl and the other leg with a second inverted U shaped passage somewhat higher than the former; a duct leading from the air chamber to a point in the discharge line; a supply pipe having branches leading to the storage chamber, flushing rim and air chamber; means for forcing air from the air chamber into the air trap during the filling process and for holding the air in said trap; and means for exhausting air from said trap during emptying process. 90 95 100 105 110 115

12. In a device of the character described, a suitable bowl; a chamber, for the storage of water, formed in the upper portion of said bowl; an air trap in the storage chamber; a duct leading from said air trap to the bowl; a flushing rim formed adjacent to the storage chamber having ports communicating with the bowl; an air chamber formed adjacent to the storage chamber; an overflow duct formed through the air chamber; an air trap provided by an inverted U shaped passage, one leg communicating with the bowl and 120 125 130

the other leg with a second inverted U shaped passage somewhat higher than the former; a duct leading from the air chamber to a point in the discharge line; a supply pipe having branches leading to the storage chamber, flushing rim and air chamber; a passage leading from the air chamber to the trap; means for holding the air in said air trap during the filling process; and an air passage leading from the air trap to a point in the siphon leg.

13. In a siphonic acting water closet, the combination with a suitable bowl and communicating siphon leg, of an air trap in said siphon leg, an air reservoir; and means for admitting air from the reservoir into the trap during the filling process.

14. In a siphonic acting water closet, the combination with a suitable bowl and com-

municating siphon leg, of an air trap in said siphon leg, an air reservoir, means for admitting air into the trap from said reservoir during the filling process and for exhausting air from said trap during the emptying process.

15. In a siphonic acting water closet, the combination with a suitable bowl and communicating siphon leg, of an air trap in said siphon leg, an air reservoir and a connection between said air reservoir and air trap.

In testimony whereof we affix our signatures in the presence of two witnesses.
